Nelson M. Donald

UNITED STATES PATENT OFFICE

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON SOLES

Application filed March 12, 1925. Serial No. 15,093.

This invention relates primarily to machines for operating upon soles. The invention is illustrated as embodied in a machine designed for providing an insole with positioning surfaces to be utilized in shoemaking operations.

In a co-pending application of the present applicant filed February 12, 1925, now Letters Patent No. 1,674,060, granted June 19, 1928,

10 is disclosed a method and a machine relating to the lasting of the toe of a shoe, a characteristic of which is that a last and insole are each provided with a plurality of positioning surfaces in spaced locations, preferably provided 15 by positioning holes, by the use of which the insole, the last and the shoe upper materials, which are to be shaped thereon, may be positioned quickly and accurately in relation to lasting devices of a lasting machine.

20 An important object of the present invention is to provide a machine particularly adapted for use in preparing such an insole and, more specifically, a machine by the use of which positioning holes may be formed in an 25 insole in definite, predetermined relation to the edge contour of the insole and also, in the case of a welt insole, to the insole rib and preferably in relatively close proximity to the rib.

To this end, the invention, in one aspect, 30 comprises an improved machine for operating on soles and more particularly for forming in insoles positioning holes of the character just described. In the particular embodiment of the invention herein illustrated, the machine 35 is constructed and arranged to provide an insole with three positioning holes in predetermined, spaced relation to the contour of the insole and adapted to be used in carrying out the method claimed in Letters Patent No. 40 1,674,060 hereinbefore referred to but, in some aspects, the invention is not limited to such embodiment and use.

The invention will now be described in detail in connection with the accompanying drawings, which illustrate a preferred embodiment of the invention, the scope of which is indicated by the appended claims.

In the drawings,

50 Fig. 1 is a side elevation of an insole punching machine of which the supporting column

and the treadle mechanism (not illustrated) may be of any known or suitable construction;

Fig. 2 is a plan view of the sole support and of the gaging devices, an insole being shown in contact with each of the gages; and

Fig. 3 is a perspective view of most of the parts shown in Fig. 2 and of the punches and their associated parts.

As illustrated, 10 indicates a flat, horizontal sole support which may include a strip or plate 12 of brass or the like to provide a suitable cutting surface for the punches. Secured to the upper surface of the sole support is an end or toe gage 14 while two side gages 16 are pivoted upon vertical studs 18 extending through the sole support and provided with bell crank levers 20, adjacent arms of which have meshing gear segments 22. The other arms 24 of the bell cranks are connected by a tension spring 26 which tends to move the free ends of the gages 16 toward each other but their movement of approach is limited by the engagement of an adjustable screw stop 28 with a lug 30 formed as an extension of one of the bell cranks 20. Another pair of side gages 36 are likewise provided with studs 38 pivoted in the sole support and connected together by gear segments 40 and also drawn toward each other by a spring 42, the movement of approach being limited by an adjustable stop 44.

It may be noted that if the toe gage 14 is removed and the adjusting screws 38 and 44 are so positioned that the two pairs of side gages 16 and 36 may be brought by their springs 26 and 42 into contact, these two points of contact will determine a straight line which passes through the gage 14 when in position and which may be termed the "center line" of the forepart of an insole positioned by said gages. Because the gages are geared together, the contacting surfaces of the two gages of each pair are always at equal distances from this center line, as will be developed hereinafter.

The sole support 10 is secured firmly in predetermined position to the machine frame 50 which, as illustrated, includes an overhanging arm provided with a vertical bearing 52 in which is mounted a vertically

reciprocating plunger 54 secured against rotation in the bearing by a key 56. Secured at the lower end of this plunger is a punch holder in the form of a block 58 having a vertical stud 60 extending into a socket 61 in the lower end of the plunger, a key 62 holding the stud against rotation in the plunger and a set screw 64 securing the punch holder to the plunger. Three hollow punches 66 are secured in predetermined position in the holder 58 and normally extend only part way through a stripper in the form of a plate 68 to which is secured a vertical rod 70 slidable through the punch holder 58 and through the stud 60. A compression spring 74 is interposed between the bottom of a socket 76 in the punch holder 58 and the top of the stripper plate 68 while into the upper end of the rod 70 is threaded a headed screw 78, the head of which normally rests against the bottom of a socket 80 in the top of stud 60.

The plunger 54 is adjustably connected by a screw, stud 82 to a block 84 having a horizontal guideway 85 in which fits a block 86 having a hole in turn fitting an eccentric pin 88 at the end of the main shaft 90. A pin 89 fixed in the plunger extends into a guideway at the lower end of block 84 to aid in maintaining the block in proper position relatively to the plunger. The shaft may be connected through a clutch 92 to a belt pulley 94. The clutch is controlled through mechanism, designated generally by 96, which may be actuated by a treadle (not shown). This driving and stopping mechanism, which may be of any appropriate construction, such for example as that shown and described in U. S. Patent No. 1,087,578, Hadaway, is so arranged that the attendant, by depressing the treadle may connect the pulley 94 with the shaft 90 and cause the plunger 54 and the parts carried thereby to make one complete reciprocation after which the pulley 94 will be disconnected from the shaft. Thus the punches will make only a single cutting stroke for each depression of the treadle.

As already indicated, the specific machine illustrated in the drawings is particularly designed for punching a plurality of positioning holes H in predetermined relation longitudinally, laterally and angularly with respect to the rib R of a welt insole S. In using the machine for punching these holes, the adjusting stops 28 and 44 are preferably so positioned that the gages 16 and 36 will be held by their springs 26, 42, in their innermost positions, somewhat nearer together than the width of the insole at the corresponding distances from its toe end. With the punches and other parts in the positions shown in Fig. 1, the insole S will be laid upon the table 10 by the attendant and pressed rearwardly between the gages 16 and

36 until its toe end comes into contact with the gage 14. As the insole is thus moved longitudinally between the side gages and along the sole support, the gages of each pair will be moved away from each other against the resistance of springs 26, 42, the attendant allowing the insole to center itself under the action of these gages, so that, when it reaches the toe gage 14, each of the gages will press against the insole edge. Thus the insole will occupy a definite, predetermined position longitudinally, laterally and angularly relative to the sole support and to the punches 66. The attendant will then actuate the clutch to cause the punches to form the holes H in predetermined relation to the rib R and to the contour of the insole, the stripper 68 forcing the insole off the punches as they rise.

Having thus indicated the object and nature of the present invention and having thus described in detail a preferred embodiment thereof, what I claim as new and desire to secure by Letters Patent of the United States is:

1. In a machine for punching in an insole a plurality of positioning holes in predetermined relation to the insole contour, the combination of a flat, horizontal sole support, a vertically movable plunger, three spaced punches carried by the plunger, means for maintaining said plunger and punches in a predetermined angular relation to each other and to the sole support, gaging devices for locating the toe portion of an insole in predetermined position upon said sole support and relatively to said punches comprising a toe gage, a pair of connected side gages relatively near the toe gage, another pair of connected side gages located at a substantially greater distance from the toe gage, both pairs of gages being movable in a single plane parallel to the sole engaging surface of said support, adjustable means for limiting, independently for each pair of gages, the minimum distance between the two gages of each pair, and yielding means for pressing the gages of each pair toward each other and against the edge of an insole as it is moved longitudinally between said gages and along the sole support.

2. In a machine for punching in an insole a plurality of positioning holes in predetermined relation to the insole contour, the combination of a sole support, a single, vertically movable, cylindrical plunger, a plurality of punches carried by the plunger, means for maintaining said plunger and punches in a predetermined angular relation to each other and to the sole support, and gaging devices constructed and arranged to contact exteriorly with a rounded end and with adjacent portions of the sole and to locate the sole in predetermined position longitudinally, lat-

erally and angularly relative to the punches.

3. In a machine for punching in an insole a plurality of positioning holes in predetermined relation to the insole contour, the combination of a sole support, a power shaft, a plunger, actuating connections between said shaft and said plunger, a punch holder and a yielding stripper carried by the plunger, three punches mounted on the holder and so located as to form positioning holes in the insole, one near the toe end thereof and two rearwardly therefrom and near the sole contour, means for maintaining said plunger, holder and punches in predetermined angular relation to each other and to the sole support, and yieldingly pressed gaging devices for contacting with the curvilinear contour of the toe portion of the insole at least at four separated points and thereby locating the insole on the support in predetermined position relatively to the punches.

In testimony whereof I have signed my name to this specification.

ARTHUR F. PYM.
